[57] CLAIM

The ornamental design for a hand held self contained window washer, as shown and described.

DESCRIPTION

FIG. 1 is a front elevation of the hand held self contained window washer showing my new design;

FIG. 2 is a side elevation of the washer taken from the left side of the washer shown in FIG. 1;

FIG. 3 is a top view;

FIG. 4 is a side elevation of the washer taken from the right side of the washer as shown in FIG. 1;

FIG. 5 is a bottom view; and,

FIG. 6 is a rear elevational view of the washer shown in FIG. 1.
